UNITED STATES PATENT OFFICE.

PHILLIP C. CLOSE, OF AUGUSTA, GEORGIA.

PITMAN.

SPECIFICATION forming part of Letters Patent No. 337,557, dated March 9, 1886.

Application filed October 19, 1885. Serial No. 180,244. (No model.)

To all whom it may concern:

Be it known that I, PHILLIP C. CLOSE, a citizen of the United States, residing at Augusta, in the county of Richmond and State 5 of Georgia, have invented certain new and useful Improvements in Pitmen, of which the following is a specification, reference being had therein to the accompanying drawings.

My invention relates to pitmen suitable for 10 harvesters, saw-mills, and other machinery in which oil is made to automatically reach the journal-bearings from reservoirs formed within the pitmen; and the objects of my invention are to produce an inexpensive, efficient, 15 and durable self-oiling pitman-rod, provided with perforated plates and absorbent material to retard and regulate the flow of oil to the bearings.

The invention will first be described in connection with the drawings, and then be pointed out in claims.

In the drawings, Figure 1 is a longitudinal section of the pitman. Fig. 2 is also a longitudinal section taken at right angles to Fig. 25 1. Fig. 3 is a longitudinal section of the pitman-rod with the end bearings removed.

The pitman-rod A is made tubular, and has secured within a tightly-fitting partition, a, either half-way of the length of the tube or 30 near either end, but preferably nearer its upper end, to form two independent chambers, a', to contain oil. Each chamber is provided with an oil-hole closed by a thumb-screw, a', or any other suitable air-tight stopper.

35 To partly check the flow of oil toward the outer end of the oil-chamber, there is packed therein tow, wool, or preferably sponge, b, between disks c, of perforated sheet metal or of woven wire, the edge of the inner disk resting either upon a shoulder, a³, formed within the hollow 40 pitman or upon pins a⁴, driven transversely across said hollow rod.

To retain the perforated outer disk c upon the sponge b, recessed plugs d, of bronze, are 45 placed thereon, and said plugs have a small vent or hole, d², for the oil to pass through and reach the journals of the pitman. Said hole d² is drilled either axially or diagonally through each plug. The upper end of the

pitman-rod has screwed thereon the T-head 50 or bearing B, to receive the wrist-pin projecting, as usual, from the face of the crank-wheel. At the opposite end of the pitman-rod is placed a steel ball, E, resting upon the lower plug, d, or upon the end of the tube. It is 55 retained in position by the lower box, B², screwed on the end of the pitman-rod. The ball has small grooves e in its periphery, to conduct oil from the reservoir upon the frictional surfaces of the lower box. It is also 60 provided with a diametrical hole to receive the connecting-pin F, projecting from an arm, F², secured to the cutter-bar of a mowing-machine or other part of a machine carrying a pitman. By this construction the oil-chambers can contain enough oil for at least one 65 day in use. The sponge packing arrests all the impurities that may be in the oil, and checks its spouting against the end bearings under the rapid reciprocating motion to which it is 70 subjected.

Having now fully described my invention, I claim—

1. The combination of a tubular pitman-rod and its transverse partition a with perforated disks c and packing b at each end, substantially as and for the purpose described. 75

2. The combination of a tubular pitman-rod and its transverse partition with the perforated disks c, packing b, and perforated plug d at each end, substantially as and for the purpose described. 80

3. The combination of a tubular pitman-rod, its transverse partition, perforated disk c, packing b, and perforated plug d with a diametrically-bored ball, E, having peripheral grooves, substantially as and for the purpose described. 85

4. The combination of a tubular pitman-rod with a transverse partition, a, therein, substantially as and for the purpose described. 90

In testimony whereof I affix my signature in presence of two witnesses.

PHILLIP C. CLOSE.
